Inventor,

F. B. Abbott,

By Southgate & Southgate, Attn:

UNITED STATES PATENT OFFICE.

FREDERIC B. ABBOTT, OF LYNN, MASSACHUSETTS, ASSIGNOR TO SAMUEL PORTER & CO., OF WORCESTER, MASSACHUSETTS.

LAST.

SPECIFICATION forming part of Letters Patent No. 660,321, dated October 23, 1900.

Application filed January 17, 1899. Serial No. 702,385. (No model.)

To all whom it may concern:

Be it known that I, FREDERIC B. ABBOTT, a citizen of the United States, residing at Lynn, in the county of Essex and State of Massachusetts, have invented a new and useful Last, of which the following is a specification.

This invention relates to that class of lasts having body and heel portions connected together by hinges; and the object of this invention is to provide a hinged last of this class with a spring for normally holding the parts of the last in line with each other, so as to insure uniformity in the size of shoes lasted on any one particular last.

15 To this end the invention consists of the parts and combinations of parts, as hereinabove described, and more particularly pointed out in the claim at the end of this specification.

20 In the accompanying drawings, Figure 1 is a side view of a last constructed according to this invention. Fig. 2 is a side view partially broken away to show the form of spring preferably employed, and Fig. 3 is a similar 25 view showing the parts of the last in a different relative position.

In the use of a last in which the body portion and heel portion are hinged together, so that the last can be withdrawn by turning up 30 the heel portion, as illustrated in Fig. 3, it happens frequently that the parts of the last are not fully straightened out into line with each other during the lasting operation, and this in practice has been found to be objectionable, as it results in more or less variation in 35 the length of shoes lasted upon the same last. To overcome this objection, I have provided a hinged last in which a spring is arranged to normally hold the parts in line with each 40 other, so as to insure uniformity in the shoes lasted thereon, while at the same time the spring is arranged to yield or have sufficient flexibility so that the last can be readily withdrawn from a shoe.

45 Referring to the drawings and in detail, a last constructed according to my invention preferably comprises a body portion A and a heel portion B. A kerf is cut in the portions A and B to receive a hinge, as C, the sides of 50 the kerf being preferably filled with leather

or other flexible material, as D. The hinge C is secured in place by screws or rivets, as shown by dotted lines in Figs. 2 and 3. A socket is bored in the body portion A of the last to receive a spring E, which engages the 55 end of a wooden or metal dowel or pin F.

When the body and heel portions of the last are turned with respect to each other to draw a last, as illustrated in Fig. 3, the pin F will be forced back in its socket, compressing the 60 spring E; but the spring E has sufficient elasticity to normally hold the parts of the last in line with each other with sufficient stiffness to insure shoes lasted being of a uniform size. By this arrangement of pin or plug F 65 and spring E, I have provided a construction which in practice I have found will give that degree of rigidity or stiffness which is required in the use of hinged lasts for holding the body portion and heel parts in line with 70 each other during the lasting operation—that is to say, by employing a last having body and heel parts with inclined faces leaving an angular space above the hinge and by employing a coiled spring and pin mounted in 75 one of the said parts, so as to extend across the open angular space and bear upon the inclined face of the other part at an oblique angle thereto, I have provided an arrangement by means of which a comparatively 80 weak spring will secure sufficient leverage to hold or lock the parts of the last in line with each other, so that a considerable force can be exerted without closing or operating the hinge of the last. Furthermore, by this arrangement I have provided a construction in which the degree of stiffness or locking action of the plug or pin can be varied without changing the stiffness of the springs employed—that is to say, by simply boring sockets for receiving the spring at various angles to vary the inclination of the pin or plug F with respect to the surface that it engages 85 the pin or plug F will hold the parts of the last in line with each other with greater or 90 less degrees of stiffness, as may be required.

I am aware that changes may be made in the details of the construction of my last by those who are skilled in the art without departing from the scope of my invention as 100

expressed in the claim. I do not wish, therefore, to be limited to the form of construction herein illustrated; but

What I do claim, and desire to secure by 5 Letters Patent of the United States, is—

In a last, the combination of a body part, a heel part, a hinge connecting the body and heel parts, said parts having inclined faces leaving an open angular space above the 10 hinge, and a coiled spring and pin mounted in a socket in one of said parts to exert a constant pressure tending to hold the parts

of the last in line with each other, said pin being arranged to extend across the open angular space and normally bearing on the inclined face of the other part at an oblique angle thereto, substantially as described. 15

In testimony whereof I have hereunto set my hand in the presence of two subscribing witnesses.

FRED. B. ABBOTT.
